UNITED STATES PATENT OFFICE.

HAROLD E. AUSTIN, OF LOUISVILLE, KENTUCKY, AND JESSE C. COOK, OF JEFFERSONVILLE, INDIANA, ASSIGNORS TO AMERICAN CREOSOTING COMPANY, OF LOUISVILLE, KENTUCKY, A CORPORATION OF INDIANA.

BOLSTER-ARM CAR.

Application filed December 8, 1922. Serial No. 605,728.

To all whom it may concern:

Be it known that we, HAROLD E. AUSTIN, of Louisville, in the county of Jefferson, State of Kentucky, and JESSE C. COOK, of Jeffersonville, in the county of Clark, State of Indiana, have invented certain new and useful Improvements in Bolster-Arm Cars; and we do hereby declare the following to be a full, clear, and exact description of the invention, such as will enable others skilled in the art to which it appertains to make and use the same.

In Letters Patent No. 805,214 granted November 21, 1905, on an application of Cuthbert B. Lowry and Richard Bernhard, there is shown and described a timber car for wood impregnating cylinders wherein longitudinal side sills and transverse end sills fastened together at their points of intersection are employed for holding the timber charge. The end sills in the patent are shown as having their ends curved upwardly and outwardly so that they not only form a connection between the side sills but also bolster arms to retain the timber in position, serving as fixed guides in the piling of such timber on the car. In the use of bolster arm cars of this type difficulty has been experienced in getting a car of sufficient strength without sacrificing cylinder capacity, and it has also been observed that in such known types of cars the timber, being in a soft state after seasoning in the cylinder, is mutilated by the sharp edges of the supporting members cutting the fibers of the wood, and annoyance has frequently been encountered in the derailing of the cars by bowed or warped timbers striking the ends of the end sills in going around curves. It is the object of our invention to so construct a car of this class of maximum strength and carrying capacity and one wherein the parts are so fabricated and arranged as to transport the material to be treated without danger of injury to the same, the retaining means for the timbers being so placed as to negative danger of derailing by the load.

Our improved car is shown in the accompanying drawings wherein Figure 1 is a top plan view, the bail being removed; Figure 2 is an end elevation; and Figure 3 a side elevation, portions of the wheels in the

latter figure being broken away. Figure 4 is an enlarged detail section on line 4—4, Figure 1.

The frame of our improved car, includes side sills 1 and end sills 2, the former preferably formed of channel iron and the sills 2 of angle bars. The sills are appropriately bolted and braced at their points of intersection. This frame is supported on carrying wheels 3 whose revolving axles 4 are mounted in bearings 5 hung from the side sills. Each of the side sills has a dropped portion 6 centrally disposed between the ends of such sills and this dropped portion is reinforced by structural steel angle bars 7. Extending transversely of the frame between the two side sills and centrally of the length of these sills is a casting 8. This casting is riveted to the side sills and serves to strengthen the frame as well to form, in part, a support for the bolster arm 9. The casting 8 has a centrally disposed bore 10 to receive a pivot pin 11 passed through a bore 12 in the arm 9, a cotter pin 13 holding the pin 11 in place. The arm 9 in addition to the support given it by the casting 8 rests, with its load, directly upon the side sills and the upper flange of the angle bars 7. The upwardly extending sides of the bolster arm are curved to conform to the cylinder walls and the tie-bearing surface of the arm is rounded off along its longitudinal sides, as at 14, so that the fibers of the wood will not be damaged by engagement with the edges of the bolster arm. A bail 15, parts of which are shown in Figure 2, is suitably connected with the bolster arm to retain the timber in position.

In addition to the dropped portion of the side sills, each end of these sills is depressed so that the end sills 2 which lie thereover will be in a plane lower than the lowermost bearing surface of the bolster arm. Each end of the end sills is downwardly inclined as at 16 so that there can be no danger of bowed or warped timber striking the ends of these sills in rounding corners. Instead of the usual sharp angles between the horizontal and vertical portions of the end sills we provide a rounded surface 17 to prevent any possible cutting into the treated timber.

The advantages of our invention will be apparent. It will be noted that by the de-

scribed construction we are enabled to provide a car of maximum carrying capacity without in any way curtailing the strength thereof and that the arrangement of the parts is such that the timber is not liable to be damaged in transit, nor is there danger of derailing a car by bowed or warped timbers striking the ends of end sills in rounding corners, the single bolster arm aiding to this end.

We claim as our invention:

1. A timber car for wood impregnating cylinders including a frame having longitudinal side sills and end sills, and an upwardly facing concaved bolster arm supported by said side sills.

2. A timber car for wood impregnating cylinders including a frame having longitudinal side sills and two end sills and an upwardly extending bolster arm supported by said side sills, the bearing surface of said arm having rounded longitudinal sides.

3. A timber car for wood impregnating cylinders including a frame having longitudinal side sills, end sills and a member connecting said side sills intermediate their length, and an upwardly facing concaved bolster arm pivotally mounted on said connecting member.

4. A timber car for wood impregnating cylinders including a frame having longitudinal side sills and two end sills and an upwardly facing, concaved bolster arm supported by said side sills, the entire bearing surface of such arm being on a plane higher than said end sills.

5. A timber car for wood impregnating cylinders including a frame having longitudinal side sills and two end sills, the ends of said end sills being downwardly inclined and the outermost edges of such sills being rounded, and an upwardly extending bolster arm supported by said side sills, the bearing surface of said arm having rounded longitudinal sides, such surface being on a plane higher than said end sills.

6. A timber car for wood impregnating cylinders including a frame having longitudinal side sills, two end sills, the ends of said end sills being downwardly inclined and the outermost edges of said sills being rounded, a member connecting said side sills intermediate their length, and an upwardly extending bolster arm pivotally mounted on said connecting member, the bearing surface of said arm having rounded longitudinal sides, such surface being on a plane higher than said end sills.

7. A timber car for wood impregnating cylinders including a frame having longitudinal side sills and two end sills, said side sills having a dropped portion, a casting extending transversely between the dropped portions of the side sills, and a bolster arm mounted on said casting and in part sup-

ported by the dropped portion of said side sills.

8. A timber car for wood impregnating cylinders including a frame having longitudinal side sills and two end sills, said side sills having a dropped portion, a casting extending transversely between the dropped portions of the side sills, and a bolster arm mounted on said casting and in part supported by the dropped portion of said side sills, the upwardly extending portions of said arm being curved to conform to the enclosing cylinder, and the bearing surface of said arm having rounded longitudinal sides and such surface being on a plane higher than said end sills.

9. A timber car for wood impregnating cylinders including a frame having longitudinal side sills and two end sills, said side sills having a centrally disposed dropped portion, and a transversely extending bolster arm spanning the space between said side sills and in part supported by the dropped portion of each side sill, the entire bearing surface of such arm being on a plane higher than said end sills.

10. A timber car for wood impregnating cylinders including a frame having longitudinal side sills formed of channel iron and two end sills, each formed of angle bars, said side and end sills being fastened together at their points of intersection, said side sills having a centrally disposed reinforced dropped portion, and the ends of said end sills being inclined downwardly, a bolster arm supported by said reinforced dropped portion of said side sills having upwardly extending portions curved to conform to the enclosing cylinder, the bearing surface of said arm being on a plane higher than the end sills and having rounded longitudinal sides.

11. A timber car for wood impregnating cylinders including a frame having longitudinal side sills formed of channel iron and two end sills formed of angle bars, said side and end sills being fastened together at their points of intersection, said side sills having a centrally disposed reinforced dropped portion, and the ends of said end sills being inclined downwardly, a transverse casting between said sills having a centrally disposed bore, a bolster arm mounted on said casting and having a pivotal connection therewith, said bolster arm being in part supported by the reinforced portion of said side sills and having upwardly extending portions curved to conform to the enclosing cylinder, the bearing surface of said arm being on a plane higher than the end sills and having rounded longitudinal sides.

12. A timber car for impregnating cylinders, including a wheeled frame having a central, transverse depression, and a bolster

arm pivotally mounted in the depression and extending laterally therein beyond the sides of the car.

13. A timber car for impregnating cylinders, including a frame, and an upwardly facing concaved bolster arm thereon having a broadened timber-supporting face, the longitudinal edges of which are rounded.

14. A timber car for impregnating cylin-

ders, including a frame having a transverse depression, a bolster arm pivotally supported in the depression and having a bearing surface above the plane of the car.

In testimony whereof we have signed this specification.

HAROLD E. AUSTIN.
JESSE C. COOK.
